(57) **CLAIM**

We claim, the ornamental design for a luminaire, as shown and described.

DESCRIPTION

FIG. 1 is a top perspective view of an embodiment of the invention;

FIG. 2 is a bottom perspective view of the embodiment of FIG. 1;

FIG. 3 is a side view of the embodiment of FIG. 1, with the opposite side being a mirror image thereof;

FIG. 4 is a front view of the embodiment of FIG. 1, with the rear view being a mirror image thereof;

FIG. 5 is a top view of the embodiment of FIG. 1; and,

FIG. 6 is a bottom view of the embodiment of FIG. 1.

The phantom lines shown in FIGS. 2 and 6 are for illustration purposes only and not part of the claimed design.

The lens of the claimed luminaire forms no part of the claimed design, the lens may have facets, lenslets or other treatments. The degree of transparency and/or opaqueness forms no part of the claimed design.

The surface treatment of the luminaire forms no part of the claimed design; a luminaire according to the claimed design may have any surface treatment.

The color of the luminaire forms no part of the claimed design; a luminaire according to the claimed design may be of any color or combination of colors.

References to "top", "bottom", "front", "side" and "rear" in the figure descriptions are not meant to require certain in-use orientation, a luminaire according to the claimed design may be used in any orientation.

1 Claim, 5 Drawing Sheets
